BREECH MECHANISM FOR GUNS HAVING
REPLACEABLE LINER

Leo Mackta, Brooklyn, N. Y.

Original application May 7, 1945, Serial No. 592,435. Divided and this application January 26, 1950, Serial No. 140,702

13 Claims. (Cl. 42—1)

(Granted under the act of March 3, 1883, as amended April 30, 1928; 370 O. G. 757)

1

The invention described herein may be manufactured and used by or for the Government for governmental purposes, without the payment to me of any royalty thereon.

This application is a division of my copending application, Serial Number 592,435, filed May 7, 1945, now Patent 2,549,832 dated April 24, 1951.

It is the main object of the invention to provide a novel breech structure for guns of particular value where a separable and readily replaceable rifled liner is used in a generally smooth bore barrel.

Another object is to provide a breech structure of particular value in connection with ammunition wherein each round consists of a unit including a cartridge enclosed within a rifled liner, the structure being so constructed and arranged as to enable axial translation of the liner forwardly into operative position within the gun tube or barrel, while positively retaining the cartridge in the breech chamber in firing relation with the firing mechanism.

Other objects and advantages will become apparent after a study of the following description in connection with the accompanying drawing wherein

Fig. 1 is a longitudinal sectional view of a gun embodying the invention and showing a round in position with its liner ready to be forced forwardly into the barrel by the retracted breech sleeve or liner.

Fig. 2 is a view corresponding to Fig. 1 showing the replaceable rifled liner rammed forwardly into the gun tube by the operatively-positioned breech sleeve and clamped in position by the sleeve.

Fig. 3 is a rear elevation of the gun with breech open.

Fig. 4 is a view corresponding to Fig. 3 but showing the breech closed.

Fig. 5 is a fragmentary longitudinal section on the line 5—5 of Fig. 3, with a round of ammunition chambered and the breech sleeve and its obturator piston at an intermediate position in opening movement to show initial action of the ejector.

Fig. 6 is a sectional view corresponding to Fig. 5, with the breech sleeve and its piston swung to fully open position and the ejector moved to fully retracted position.

Fig. 7 is a fragmentary longitudinal section on an enlarged scale of the breech sleeve and its piston and showing the firing mechanism in fired position.

Fig. 8 is a fragmentary section corresponding to Fig. 7 but showing the firing pin in cocked position.

2

to Fig. 7 but showing the firing pin in cocked position.

Fig. 9 is a fragmentary longitudinal section of the rear portion of the breech chamber, forward portion of the breech sleeve, obturator piston and means releasably connecting a cartridge to the piston.

Fig. 9A is a detail sectional view to an enlarged scale of a portion of Fig. 9.

Fig. 10 is a longitudinal section of the breech mechanism equipped with a different means for releasably connecting the cartridge and piston.

Fig. 11 is a section taken in a plane indicated by the line 11—11; Fig. 10.

Fig. 12 is a detail sectional view taken in a plane indicated by the line 12—12; Fig. 11, and

Fig. 13 is a detail view showing to an enlarged scale the two-part cocking lever and a coacting portion of the firing pin.

Referring in detail to the drawing, a base 1 has a barrel 2 rigidly attached thereto. Base 1 may be carried upon any known mount, not shown, for moving the gun in train and elevation. The barrel has a forward portion forming a bore 3 and a rear portion forming a breech chamber 4. The chamber 4 is of greater diameter than bore 3, thereby forming a shoulder 5 at the junction between the two. Interrupted threads 6 are formed in the rear portion of the walls of chamber 4. Bore 3 which is shown with a forward taper, may have a smooth surface or, alternatively, have its surface indented with small grooves or recesses to increase the friction between itself and the contacting surface of the replaceable liner, to be described later.

A breech sleeve 7 has a smooth sliding fit within the breech chamber 4. The sleeve is formed with an open forward end and a rear end closed by a head 8 which may be integral with the sleeve. The sleeve is provided with interrupted threads 9 on its rear external walls for coaction with threads 6 to lock sleeve 7 within chamber 4 when the parts are in the position shown at Fig. 2.

Base 1 has bearings 10 and 11 attached thereto in spaced aligned relation. A rod or tube 12 is journaled in these bearings at its forward portion and is held against axial movement in the bearings by collars such as 13 and 14, Figs. 1 and 2. At its rear end, tube 12 has an arm 15 fixed thereto. As seen in Fig. 3, the arm is rotatable clockwise with tube 12, movement being limited by engagement of a lug 16 with the top surface of base 1.

A rod 17 is fixed at its rear end in lever 15,

This rod passes forwardly through a central aperture in head 8 and, at its forward end has a piston 18 fixed thereto. The piston has a smooth sliding fit within sleeve 7 and, as clearly shown upon Figs. 1 and 2, the parts are so dimensioned that piston 18 lies substantially in the plane of the rear end of chamber 4. Furthermore, when sleeve 7 is in fully retracted position as in Fig. 1, its forward end just clears the rear end of breech chamber 4 and its rear end is contiguous to arm 15, while, when the sleeve is in fully advanced position as in Fig. 2, its forward end is closely adjacent shoulder 5 and its rear end is contiguous to piston 18. The sleeve has a radially extending operating handle 19 fixed to its rear end. When fully retracted, a reduced portion of this handle fits a forked lug 15a on the upper end of arm 15 as will be clear from inspection of Figs. 1 and 10. By this construction, when the parts are in the position shown in Fig. 1, sleeve 7 and arm 15 may be rotated as a unit to the position shown in Fig. 3 to thereby fully open the breech for loading.

Tube 12 has a longitudinally-extending slot 12a through the rear half of its length. The slot faces upwardly as the parts are shown in Figs. 1 and 2. A liner ejector includes a straight rod 20 slidable within tube 12, and a bent end 20a projecting upwardly through slot 12a and secured to the head 8 of breech sleeve 7 for movement as a unit therewith. The forward end of rod 20 is attached to a downwardly-bent arm 21a of an ejector rod 21. The rear end of rod 21 is turned upwardly to form an ejector portion 21b positioned to ride in and along a longitudinally-extending slot through the bottom of the portion of the barrel wall forming chamber 4. As shown in Fig. 2, the portion 21b lies in a radial passageway in the barrel and forwardly of and in contact with the rim of barrel liner 22 so that, when rod 20 is moved rearwardly with sleeve 7 portion 21b forces the liner rearwardly therewith out of the barrel.

Piston 18 has a rearwardly-opening recess 23 for the accommodation of firing mechanism shown in Figs. 7 and 8, wherein it will be noted that rod 17 is hollow and in communication with recess 23. A firing pin 24 is slidably mounted in a central aperture in piston 18 and extends rearwardly into a counterbore in the end of rod 17. The pin is urged forwardly to the firing position of Fig. 7 by a coil spring 25 acting between an abutment 26 on pin 24 and the shoulder formed by the counterbore in rod 17. The pin is fixed against rotation by means not shown.

The firing pin is held in the cocked position of Fig. 8 by a sear 27 pivoted in recess 23 and urged into operative position by a spring 28. When the firing pin is retracted to cocked position by mechanism subsequently described, sear 27 is first cammed downwardly by a latch 24a and then snaps upwardly into the position shown at Fig. 8 as the latch moves rearwardly, to hold the pin in cocked position. Clockwise movement of sear 27 to release pin 24 and permit firing movement of the pin under the urge of spring 25, is effected by a cable 29 attached at one end to the sear and guided by suitably-positioned pulleys 30 to the inside of rod 17. The cable extends through rod 17 and at its rear end is attached to a ring 31, Figs. 1, 2, and 10, whereby the cable may be pulled to manually fire the gun as by means of a lanyard.

The firing pin is automatically retracted to cocked position in response to forward translation of sleeve 7 into battery position, by a lever 32

pivoted in recess 23 on an axis at right angles to the firing pin and urged into clockwise rotation as viewed in Figs. 7 and 8, by a light spring 33. Suitable stop means, not shown are provided to limit clockwise movement of the lever to substantially the position shown at Fig. 7. As shown in detail in Fig. 13, the lower end 32a of lever 32 is pivoted at 32b to the main portion of the lever. Stops 32c on the interpivoted portions engage and prevent further clockwise movement of end 32a when this portion is in the full-line position of Fig. 13. A light leaf spring 34 secured at one end to lever 32, engages pivoted end 32a and urges it into the full-line position shown.

From Fig. 7 it is noted that the upper curved end of lever 32 projects rearwardly from the rear face of piston 18 so that, when breech sleeve 7 is moved forwardly into battery position its head 8 engages lever 32 and rotates the same counterclockwise. In response to this movement, end 32a engages abutment or collar 26 and forces the firing pin into cocked position at the same time compressing spring 25. A little before sleeve 7 reaches the position of Fig. 8, sear 27 snaps in front of latch 24a to hold the firing pin in cocked position and nose or end 32a then clears abutment 26 as the sleeve 7 moves into its limiting forward or battery position as shown in Fig. 8. The firing pin is then free to move forward under urge of spring 25 when released by a pull on cable 29 and, when sleeve 7 is again retracted, cocking lever 32 can rotate clockwise under the action of its spring 33. During this rotation pivoted end 32a engages abutment 26 and pivots against the action of spring 34, as indicated in dotted lines in Fig. 13, until, on continued clockwise movement of lever 32, end 32a is free to again move into the full-line, operative position of Figs. 7 and 13.

The cartridge and its enclosing barrel liner form a loading unit which may be packaged and loaded together. The cartridge may consist of a shell or casing 35 having a specially formed head. This head may be formed with a concentric annular channel 36. A ring 37 is secured to the rear face of the shell and has a width sufficient to form an inward flange as indicated at 38, Figs. 9 and 9A. If desired, a frusto-conical metal ring 39 may be fixed concentrically on the central portion of the cartridge head, to provide a cam surface within the groove 36, as clearly shown in Fig. 9. The head contains a primer 40 for detonating explosive charge 41 in response to firing movement of pin 24. A projectile 42 is secured within the forward end of casing 35 as by crimping the casing rim into a circumferential groove in the projectile. The metal liner 22 has a smooth fit about casing 35 and includes a base ring 22a having an integral external flange 22b to be engaged by the end of sleeve 7 when the latter is moved forwardly into battery position. A number of strips integral with base ring 22a extend forwardly therefrom in parallel helical paths and when forced forwardly to the position of Fig. 2, form rifling lands snugly fitting the barrel. Since the cartridge and liner are fully disclosed and claimed in my original application above identified, no further description of this feature is deemed necessary. Suffice it to say that when sleeve 7 is forced forward to battery position, liner 22 is engaged thereby and forced from the cartridge into the position shown at Fig. 2, where its rim or flange 22b is firmly gripped between shoulder 5 and the rim of sleeve

7 to prevent further forward movement of the liner within the barrel.

The liner 22 fits about the cartridge and therefore the latter tends to move forwardly with the liner away from piston 18, when sleeve 7 is moved into the battery position of Fig. 2. To prevent this and to retain the cartridge in firing relation with the firing pin in piston 18, means are provided to releasably connect the head of the cartridge shell with piston 18 whereby the cartridge is prevented from forward movement with liner 22 and is held in operative relation with firing pin 24. One suitable means is shown in Figs. 9, 9A, 10 and 11. The construction of the cartridge portion of such means has been previously described. The cooperating portion carried by piston 18 will now be described. A recess 43 in piston 18 opens through the forward face thereof and has a cup 44 secured therein as by threading or pressing. A latch element 45 comprises a plunger 45a fitting the cup, and having a stem 45b projecting through a central aperture in the bottom of the cup, and a button or head 45c. A spring 46 urges the latch element forwardly into the position shown in Fig. 9A. The parts are so related that, when a cartridge and its liner are loaded into the breech, and sleeve 7 and its piston 18 are swung from the position shown in Fig. 3 to the position shown in Fig. 1, head 45c rides across the rear face of the cartridge and, a little before the piston reaches final position, that is, the position shown in Figs. 9 and 9A, head 45c snaps into channel 38 and engages over the edge of flange 38 as seen in Fig. 9A to thereby secure the cartridge to the piston 17 and prevent it from moving forwardly with liner 22 when the latter is rammed into position by sleeve 7. It is contemplated that the cartridge case 35 may be of combustible material and hence consumed by detonation of the explosive contained therein. However, when it is desired to open the breech without detonation of the cartridge, sleeve 7 may be unlocked and withdrawn to the position of Fig. 1. Then, as the sleeve and piston are swung laterally about the axis of rod 12, head 45c is released from flange 38 and then cammed into recess 43 by the surface of ring 39, as will be clear from inspection of Fig. 9A. Rings 37 and 39 may also be made of combustible materials.

In Figs. 10, 11 and 12, I have shown a modified construction for securing the piston to the head of the cartridge. In these figures, the head 47 of the cartridge is formed with a peripheral rabbet 48. A disc 49 of substantially less diameter than the cartridge, is secured to the head centrally thereof and overhangs the rabbet to form a flange as will be clear from Fig. 10. A lever 50 is pivotally and slidably mounted within a radial slot in the piston as by a pin and slot arrangement 51. The lever has a hooked forward end 50a adapted, in one position of the lever, to engage over the peripheral edge of the disc. A bent leaf spring 52 is mounted within a pocket in the piston and has one arm engaging lever 50 to urge the same rearwardly from the position shown in Fig. 10. The rear arm of lever 50 projects rearwardly through a cam slot 53a formed in a sector-shaped plate 53 integral with a tube 54 journaled on rod 17. This tube extends rearwardly through head 8 and arm 15 where it has an offset operating handle 55 fixed thereto. As seen in Fig. 11, the right portion of slot 53a is concentric of rod 17, which portion merges into a left portion of gradually increasing radial dis-

tance from the axis of the rod. The rear end of lever 50 projects through slot 53a for all positions of the lever relatively to its pivot. A cam 56 overlies slot 53a and is secured at one end, as at 56a, Fig. 11, to plate 53. As clearly shown upon Fig. 12, the cam has a gradually increasing distance from plate 53. By the construction just described, when a fresh round has been loaded and the sleeve and piston have been rotated into position coaxial with the breech, that is, the position shown upon Fig. 10, handle 55 is positioned so that the end of lever 50 is at the right or radially inwardmost portion of slot 53a and, under urge of spring 52, lever 50 is in its rearwardmost position in which position its forward end lies within the piston. Now, as handle 55 is turned clockwise, plate 53 and cam 56 move correspondingly. Cam 56 first engages the adjacent end of lever 50 and forces the lever forwardly until its hooked end lies within rabbet 48. Then the lower edge of slot 53a rotates the lever counterclockwise as viewed in Fig. 10, until its hooked end engages about the periphery of disc 49 to thereby lock the piston to the cartridge so that the latter is held against axial movement when the sleeve and liner are thrust forwardly.

In order to eject the liner 22 after loading but before being rammed, means are provided as shown in Figs. 5 and 6, operated in response to transverse pivotal movement of the breech sleeve from the position of Fig. 4 to that shown at Fig. 3. To effect this function, the rear end of barrel 2 carries a housing 2a (see Figs. 3 to 6), within which an ejector lever 57 is pivoted on a pivot 58 at right angles to the bore axis of the gun. The free end of the lever is adapted to project through a slot in the barrel wall when pivoted counterclockwise from the position shown in dotted lines, Fig. 5, to the full line ejecting position of Fig. 6. The end of the lever is shaped to engage the rim 22c of a liner and to force the same rearwardly out of fully seated position as will be clear from inspection of Figs. 5 and 6. A second lever 59 is pivoted on pivot 58 closely adjacent lever 57. The two levers 57 and 59 are connected by a coil spring 60 and are so angularly related and positioned that when sleeve 7 is in the position shown in Fig. 1, ejector lever 57 is in the dotted line position of Fig. 5 and lever 59 is displaced a little clockwise from its position shown in Fig. 5 wherein its end 59a projects into the path of the sleeve as the latter is swung to open position. Thus as the sleeve is swung to the open position of Fig. 3, the lever 59 is pivoted and, through spring 60, pivots lever 57 to cause nose portion 57a of the latter to engage the rim 22c and force the liner rearwardly either to forcibly throw it clear of the gun or to enable it to be manually withdrawn.

In operation, with the breech sleeve and related parts in the position shown in Fig. 3, a cartridge and liner unit is loaded into the breech chamber as seen in Fig. 1. The sleeve and its piston are then rotated into the ramming position of Fig. 1. In the modification of Fig. 9, this movement automatically secures the cartridge to the piston to insure that the firing pin carried by the piston is in detonating relation with the cartridge and also to prevent forward movement of the cartridge with the liner.

Sleeve 7 is next forced into the breech chamber, moving the liner ahead of it into the bore. The sleeve is now given a fraction of a turn to engage the interrupted threads 6 and 9 and lock

the sleeve in battery position. As the sleeve moves into final position, its closed end engages cocking lever 32 and pivots the same to move the firing pin to cocked position, as previously fully explained. Firing may now be effected by a pull on ring 31.

After firing, the sleeve 7 is unlocked and withdrawn to the position of Fig. 1 after which the sleeve and piston are rotated as a unit about the axis of shaft 12, to the open position of Fig. 3. This movement, in the species of Fig. 9, automatically disconnects the piston from the cartridge head. Of course, such disconnection may not be necessary in case the cartridge casing is made of combustible material and is entirely consumed in the detonation of the contained explosive charge. As sleeve 7 is withdrawn, rod 21 is translated rearwardly to force the liner 22 to the position shown at Fig. 1. As the sleeve and piston unit are swung about the axis of shaft 12, the sleeve engages lever 59 as seen in Fig. 5, and pivots lever 57 either to eject the liner or to force it rearwardly so that it can be easily manually extracted.

When the cartridge lock of Figs. 10 to 12 is employed, preferably as soon as the sleeve 7 has been turned to the ramming or retracted position of Fig. 10, handle 55 is turned clockwise to first thrust lever 59 forwardly and then pivot it downwardly to cause its hooked end to engage over the rim of disc 49 and lock the cartridge to the piston in firing relation therewith in the manner previously described. Where the cartridge casing is not consumed during detonation, the handle 55 is operated in the reverse direction after firing and after sleeve 7 has been withdrawn but before it has been swung downwardly with arm 15, to thereby disconnect the casing from piston 18 and to withdraw the lever 59 within the piston so that the latter is free to swing downwardly with sleeve 7 to loading position. The operation of the means for extracting the liner from the barrel into the breech chamber in response to movement of sleeve 7 from battery to retracted position, and for extracting the liner from the chamber in response to swinging of the sleeve from retracted to loading positions is the same as previously described.

While I have shown the form of the invention now preferred by me, numerous modifications and substitutions of equivalents will occur to those skilled in the art after a study of the foregoing disclosure. Hence, the disclosure is to be taken in an illustrative rather than a limiting sense and all modifications falling within the scope of the subjoined claims are reserved.

Having now fully disclosed the invention, what I claim and desire to secure by Letters Patent is:

1. In a gun, a coaxial barrel and breech chamber, said chamber having a diameter greater than the diameter of the bore of said barrel, there being an annular, rearwardly-facing shoulder between said bore and chamber, a breech sleeve having a closed rear end and an open forward end, said sleeve being adapted to slidably fit said chamber with its forward end clamping the flanged rim of a liner against said shoulder, means mounting said sleeve for axial movement to a position clear of said chamber and for revolution about an axis external of said gun to clear the breech thereof, and means comprising a piston slidably fitting said sleeve to fire a cartridge fitting said sleeve when said sleeve is positioned forwardly within said chamber.

2. In a gun, a barrel having a bore and a

breech chamber, said chamber being of greater diameter than said bore to form a rearwardly-facing shoulder at the junction between said bore and chamber, a breech sleeve slidably fitting said chamber and movable therein from a battery position in which the open forward end of said chamber is closely adjacent said shoulder, to a retracted position clear of said chamber, said sleeve having a closed rear end, a piston slidably fitting said sleeve, a rod fixed to said piston and extending rearwardly therefrom through an aperture in the closed rear end of said sleeve, an arm fixed to said rod at the rear end thereof, bearing means fixed with said chamber and defining an axis parallel with and offset from the bore axis of said barrel, and a shaft journaled in said bearing means and secured at its rearward end to said arm.

3. A gun as recited in claim 2, and means securing said sleeve against rotation on said rod when the sleeve is retracted to rearward position on said rod.

4. A gun as recited in claim 2, there being a longitudinal slot through the wall of said breech chamber, extractor means projecting through said slot, and means responsive to movement of said breech sleeve from battery position to retracted position to move said extractor means along said slot from a forward position in the plane of said shoulder to a rearward position adjacent the rear of said chamber.

5. In a gun, a barrel having a bore and breech chamber coaxial therewith, a breech sleeve closed at its rear end only and slidably fitting said chamber, means mounting said sleeve for movement from a retracted position clear of said chamber, to a battery position within said chamber and for swinging movement when in retracted position about an axis parallel with and offset from the bore axis of the gun to a loading position, a piston slidably fitting said sleeve and swingable therewith only in a plane parallel to and abutting the rear face of said chamber, firing means carried by said piston, and locking means carried by said piston to secure thereto a cartridge in said chamber, when said sleeve is in retracted position whereby said firing means may operate to fire said cartridge.

6. A gun as recited in claim 5, said last-named means being operated automatically in response to swinging of said sleeve and piston from loading to retracted positions.

7. A gun as recited in claim 5, rod means operable manually to actuate said locking means when said sleeve and piston are in retracted position.

8. In a gun, a barrel having a bore and breech chamber coaxial therewith, said barrel being adapted to receive a removable liner by insertion through said chamber, a breech sleeve open at its forward end and slidably fitting said breech chamber for movement from a battery position in said chamber to a retracted position clear of said chamber, means locking said sleeve in battery position within said chamber, a piston slidably fitting said sleeve and limited to swinging in a transverse plane parallel to and abutting the rear face of said chamber, means mounting said sleeve and piston for swinging as a unit from retracted position of said sleeve to a loading position clear of said breech chamber, means responsive to movement of said sleeve from battery to retracted positions to extract the liner from said barrel into said chamber, and means responsive to swinging of said sleeve and piston from re-

tracted to loading positions to extract the liner from said chamber.

9. A gun as recited in claim 8, and means responsive to swinging of said sleeve and piston from loading to battery positions to lock said piston to a cartridge in said chamber.

10. A gun as recited in claim 8, and manually operable means carried by said sleeve, to lock said piston to a cartridge in said chamber when said sleeve and piston are in retracted position of said sleeve.

11. In a gun, a barrel having a bore and a breech chamber, said breech chamber being of greater diameter than said bore to form a rearwardly-facing shoulder at their meeting surfaces, a breech sleeve having a radial thickness equal to that of said shoulder and slidably fitting said chamber for translation from a battery position with its forward face adjacent said shoulder, to a retracted position clear of said chamber, a piston slidably fitting said sleeve, a rod fixed to said piston and extending rearwardly through an aperture in the closed rear end of said sleeve, means external of said sleeve mounting said rod, piston and sleeve for swinging about an axis external of said gun and parallel with the bore axis thereof, when said sleeve is in retracted position, said piston abutting the rear end of said sleeve when the latter is in battery position, a firing pin in said piston and means responsive to movement of said sleeve into battery position to cock said firing pin.

12. In a gun, a barrel having a coaxial bore and breech chamber, said chamber being of greater diameter than said bore to form a rearwardly-facing shoulder therebetween, a breech sleeve slidably fitting said chamber and having a uniform wall thickness substantially equal to the radial dimension of said shoulder, closure means to close the rear end of said sleeve, means operable to lock said sleeve in position within said

chamber, and means carried by said sleeve to fire a charge therein when said sleeve is in locked position, said last-named means comprising a piston slidably fitting said sleeve, firing pin means carried by said piston, a piston rod secured to said piston and extending rearwardly therefrom through an aperture in said closure means, and means in fixed relation with said gun and mounting said sleeve and piston for swinging about an axis parallel to and offset from the bore axis of said gun.

13. In a gun, a barrel having a coaxial bore and breech chamber, said chamber being of greater diameter than said bore to form a rearwardly-facing shoulder therebetween, a breech sleeve slidably fitting said chamber and having a uniform wall thickness substantially equal to the radial dimension of said shoulder, closure means to close the rear end of said sleeve, means operable to lock said sleeve in position within said chamber, means carried by said sleeve to fire a charge therein when said sleeve is in locked position, said last-named means comprising a piston slidably fitting said sleeve, firing pin means carried by said piston, and means mounting said piston and breech sleeve for lateral movement as a unit in planes normal to the bore axis of the gun, said piston being movable only in a plane parallel to and abutting the rear face of said breech chamber.
